FILING CABINET

John F. Reimer, Manitowoc, Wis., assignor to
Invincible Metal Furniture Company, Mani-
towoc, Wis.

Application February 4, 1946, Serial No. 645,283

2 Claims. (Cl. 312—218)

1

My invention refers to multiple drawer filing cabinets for various records and it has for its primary object to provide a cabinet simple in construction and arranged to meet standard requirements with or without a universal drawer lock. All details are so constructed and arranged that it can be produced at a minimum cost, while at the same time it is durable and will not, under long usage, develop defects due to wear, whereby proper functioning is assured.

A specific object of my invention is to provide an offset double flanged track-strip drawer support, which also serves as a casing reinforcement, the same embodying all essential features for cheap assemblage and serves as a support for floating drawer rails in conjunction with associated stopping lugs, whereby telescopic movement of the floating rails is limited.

Further objects of my invention are:

To provide floating drawer supporting rails having stopping lugs engageable with similar stopping lugs carried by the flanged track-strip, in conjunction with upper rollers and a series of anti-friction lower rollers, all engageable with offset flanged track-strips carried by the casing, whereby the telescopic floating rail element is rigidly maintained against sagging when a drawer is fully opened.

To provide a flanged vertically disposed U shaped locking-bar housing at the front of the casing, which serves as a brace and locking-bar jacket, when it is desired to convert the cabinet into a universal lock means for all drawers, the housing being provided with permanent fins for engagement with spring controlled, manually actuated, bolt latches, carried by each drawer for releasing the same.

To provide a universal locking-bar which may readily be inserted into the U shaped housing when the cabinet is to be used with a universal drawer locking means, the said bar having stop wings extending through openings in the housing for locking all drawers, by engagement with the spring controlled bolt latches, the same being carried by each drawer, whereby they are all securely locked irrespective of any release movement of the spring controlled bolt latches.

To provide a weakened knock-out plate, at the front upper face of the cabinet, in alignment with the U shaped housing, for the insertion therein of a key receiving locking barrel, forming part of a spring controlled stem slideably mounted in a bracket unit, which bracket unit also contains a spring controlled pivoted lever, adapted to be coupled to the end of the univer-

2

sal locking-bar, whereby the same is reciprocated within its housing to simultaneously lock or release all drawers by key-actuated means associated with a locking barrel.

To provide a single anchoring screw for the locking barrel bracket unit, whereby the same may readily be positioned and permanently secured within the cabinet casing.

To provide pairs of adjustable follower compression supporting arms for each drawer compressor, slideably mounted upon stamped rack-bars, the said rack-bars being readily assembled by sliding the same upon the edges of a flanged wing-strip. The rack-bars, when placed in position, are inserted through a mouth of the drawer back wall and thereafter they are secured by a tooth of the drawer back wall in the line of travel of lips carried by said rack-bars, whereby they are permanently anchored.

To provide inside clearance of the drawer surface by offset channels formed in the side walls of the drawers for slideably receiving the stamped rack-bars, the same having beaded edges engaging the flanges of the wing-strip.

To provide a pair of feet extending from the compression panel, having grooved edges slideably engaging the beaded edges of the rack-bars, whereby the panel is adjusted.

To provide a pair of spring controlled plungers carried by each panel, for selectively locking the panel in a predetermined position relative to the length of the drawer.

To provide an inverted V shaped plate, carried by each panel and engageable with the spring controlled plungers, whereby, upon depression of the plate, the plungers are retracted from locking connection with the teeth of the rack-bars.

To provide a manually actuated spring controlled slideable latch bolt mounted upon the front wall of the drawer for engagement with the offset fins of the U shaped locking-bar housing, whereby the drawers are individually fastened or released when the cabinet is not equipped with a universal locking-bar.

To provide each flanged track-strip with an upper interrupted flange at its rear end portion, spaced backwardly of its stop lug, whereby the floating rails may be angularly positioned and inserted under the interrupted flange and thereafter dropped downwardly to their proper horizontal seat within the channel strips, whereby the stop lugs of the floating rails will assume their proper aligned position relative to the companion stop lugs of the channel strips.

With the above and other objects in view,

which will appear as the description proceeds, the invention resides in the novel construction, combination and arrangement of parts, substantially as hereinafter described, and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:

Fig. 1 represents a fragmentary face view of a cabinet and slideable drawer therein, with parts broken away and in section to illustrate the slideable locking-bolt for the drawer and floating rails together with the universal locking-bar and associated parts.

Fig. 2 is a fragmentary longitudinal sectional view of the cabinet particularly illustrating the universal drawer locking means, the section being indicated by line 2—2 of Fig. 1.

Fig. 3 is a magnified detail sectional elevation illustrating the bracket carried key controlled lock and release mechanism for raising and lowering the universal locking-bar, the section being indicated by line 3—3 of Fig. 4.

Fig. 4 is a plan sectional view of the same, the section being indicated by line 4—4 of Fig. 3.

Fig. 5 is a cross section of the locking mechanism, the section being indicated by line 5—5 of Fig. 3.

Fig. 6 is another cross section of the same, the section being upon a plane indicated by line 6—6 of Fig. 3.

Fig. 7 is another fragmentary cross section of the locking mechanism upon a plane, indicated by line 7—7 of Fig. 3.

Fig. 8 is a sectional plan view of the manually actuated reciprocative bolt mounted in the front wall of the drawer, particularly illustrating the lock and release fin and stop-wing associated with the reciprocative locking-bar, the section being indicated by line 8—8 of Fig. 1.

Fig. 9 is a fragmentary face view of the upper front corner of the cabinet illustrating in dotted lines the knock-out plate, which plate is removed when the universal lock and release mechanism is to be assembled in the structure.

Fig. 10 is a longitudinal sectional view of the upper portion of the cabinet and a drawer extended in its full open position from the open front of said cabinet, the section being indicated upon line 10—10 of Fig. 1.

Fig. 11 is a detail fragmentary side elevation particularly illustrating one of the flanged channel-strips and its stop lug, with the floating rail removed, which channel-strip is secured to the side wall of a cabinet, the same being partly in section as indicated by line 11—11 of Fig. 13.

Fig. 12 is a detail plan sectional view of a portion of the channel-strip, the section being indicated by line 12—12 of Fig. 11.

Fig. 13 is a cross section of the channel-strip and floating rail, the section being indicated by line 13—13 of Fig. 10.

Fig. 13a is a detail fragmentary face view of the same.

Fig. 14 is a plan sectional view of the channel-strip and floating rail, particularly illustrating the stop lugs, said section being indicated by line 14—14 of Fig. 10.

Fig. 15 is a detail plan sectional view particu-

larly illustrating the aligned stop-knuckles carried by the drawer and floating rail, the section being indicated by line 15—15 of Fig. 10.

Fig. 16 is a cross-section of the drawer, the section being indicated by line 16—16 of Fig. 10 and particularly illustrating the lock and release plungers carried by the follower panel, whereby said panel is adjusted by a manual operation.

Fig. 17 is a fragmentary plan sectional view of the same, the section being indicated by line 17—17 of Fig. 16.

Fig. 18 is a longitudinal sectional elevation of the panel plungers actuating mechanism, the section being indicated by line 18—18 of Fig. 16.

Fig. 19 is a detail sectional plan view of one of the rear corners of the drawer and rack-bar assemblage, particularly illustrating the lock mechanism for the rack-bar after its insertion through the drawer mouth, the section being indicated by line 19—19 of Fig. 10; and

Fig. 20 is a sectional plan view of the front corner of the drawer, the section being indicated by line 20—20 of Fig. 10.

Referring by characters to the drawings, 1 indicates the rear wall of a filing cabinet and 1' the side walls of the same, the said cabinet having an upwardly flanged opening 1" for a slideable drawer A, the bottom of the drawer opening being formed by a partition strip 2.

Spot welded, or otherwise secured, to the side walls 1' of the cabinet is a pair of rail strips 3 having a bottom U shaped flange 3' extending throughout its length and an upper similar flange 3", the same being terminated at a point rearwardly of the front end of said rail strip.

The rail strip has secured thereto a stop lug 4 positioned slightly in advance of the fragmentary U shaped flange 3", it being understood that the forward end of the rail strip, at its bottom portion, is lapped over and secured to the partition strip 2.

Slideably mounted in each rail strip 3 is a floating rail 5 having inturned upper and lower flanges 5'—5", respectively. The rail has pivoted therein, at its lower portion, a plurality of anti-friction rollers 6—6, which rollers travel upon the bottom face of the lower flange 3'. The upper flange portion 5' of the floating rail has pivoted therein an anti-friction roller 7, which roller rides upon the face of the fragmentary flange 3", whereby the floating rail is held rigidly in its vertical position when said rail is fully extended.

The side walls 23 of the drawer A have extended therefrom flange strips 8—8, which strips support the drawer upon the last two rollers 6 when the drawer is extended, and the rear roller 6 also supports the drawer when it is nested within the cabinet. As indicated in Fig. 10, when the drawer is fully extended, a knuckle 6' engages a corresponding knuckle 6", whereby the drawer is stopped.

It will also be noted that the pair of rails 5, as best shown in Fig. 14, have secured to the walls thereof stop lugs 4', which stop lugs, having bumpers at their ends, engage each other when the floating rails have reached their extreme extended position, as indicated in Fig. 10 of the drawings.

From the foregoing description, it will be noted, due to the fact that the upper flange 3" of the rail strip is stopped off a considerable distance from the front of said rail strip, that the floating rails may conveniently be inserted into position, with reference to said rail strip, by slightly inclining the outer ends of said rails upwardly, whereby

their inner ends will readily enter between the flanges 3' of the rail strips and thereafter, when said rails are dropped to their horizontal position of rest, their stop lugs 4' will be positioned rearwardly of the rail-strip stop lugs 4, whereby these associated elements are interlocked.

Secured to the front corners of the casing walls, adjacent to the mouth of each drawer opening, are a pair of U shaped flanged housings 9-9', which housings serve as reinforcing members for stiffening the corners of the casing.

When it is desired to equip a cabinet with a universal locking mechanism, the flanged housing 9' is utilized for inserting therein a locking-bar 10 for all drawers, as best indicated in Figs. 1 to 4 inclusive and Fig. 8. The said bar 10 is readily inserted into the housing through an opening in the bottom of the cabinet (not shown). The locking-bar 10 carries a stop-wing 10' for each drawer, the same being extended through slots in the housing 9' and positioned at points approximately midway of the height of each drawer side.

Each stop-wing projects outwardly, directly above a wedge-shaped fin 11 upset from the housing 9'. As best indicated in Figs. 1, 2 and 8, the fin 11 normally engages an offset lip 12' of a reciprocative bolt 12, which bolt is carried by the front wall of the drawer and is held in its locked position, relative to the fin, by a coil spring 13. Hence, the above noted locking position of the bolt will function when the drawer is not equipped with a universal locking-bar 10. To free the bolt of each drawer from its locking fin 11, as indicated in dotted lines, the latch bolt, which carries a reciprocative button 12" extending from the front wall of the drawer, is moved from left to right. Thus it will be seen that, under the above noted conditions, each drawer has an individual lock, or fastener.

In order to neutralize the locking bolt, when the cabinet is equipped with a universal locking bar, the same is effected as follows: When it is desired to lock all drawers, the universal locking-bar 10 is moved downwardly by the key actuated mechanism, to be hereinafter described, as best shown in Fig. 3 of the drawings. In this position each locking-bar stop-wing 10', as indicated in dotted lines of Fig. 2, is brought into engagement with the lip 12' of the latch bolt.

Hence, owing to the fact that the stop-wing is of a width sufficient to overlap the bolt lip 12', the locking connection between the drawer and locking bolt will be maintained. This locking connection is effected, even though the bolt is drawn from left to right, as indicated in dotted lines of Fig. 8. When so drawn, the lip of the bolt, even though moved to its full limit, cannot be disengaged from the stop-wing 10'.

To release all drawers from the universal lock, the locking-bar 10 is moved upwardly, as best shown in Fig. 2 of the drawings, whereby the bolt lip 12' is cleared from the stop-wing 10' and thereafter all bolts 12 may be individually actuated to release their associated drawers.

It is apparent when a universal lock is to be added to the assemblage, the knock-out plate, shown in Fig. 9 previously mentioned, is removed. A key controlled barrel 14, which is slideably mounted in a bracket 15, is inserted through the knock-out aperture, the same being extended beyond the front wall of the cabinet, whereby access is had thereto by a key, as indicated in dotted lines of Fig. 3.

The barrel 14 has connected thereto a stem 16 having a tail piece 16' which is slideable in an

opening in the bracket. Interposed between this bracket portion and stem is a coil spring 17, the same exerting pressure upon the barrel to maintain the same in an extended outward position, as indicated in dotted lines of Fig. 3.

When the bracket 15, containing the locking unit, is fitted to the top and front wall corner of the casing, the said bracket is confined by a single screw 18, in conjunction with the barrel support at the front end. Hence, this is all that is required to confine the assembled key unit.

Pivottally mounted in the bracket 15 is a lever 19, the end of which lever is connected by a pivot stud 19' to the end of the locking bar 10. A stud 20, which extends from the stem 16, engages an angular slot 21 formed in the lever 19. A spring 19" connects the locking-bar 10 and lip of the bracket 15 to hold the bar in its unlocked position.

From the foregoing description it is apparent, when all drawers are locked, the barrel 14 is in the position indicated in full lines of Fig. 3. In said position the locking-bar is moved downwardly by the lever 19 due to the engagement of the stud 20 with the lever slot 21.

When this inward movement of the barrel and associated parts is effected, a key controlled latch 22 enters a slot 22' in the bracket, whereby the assemblage is held in the position shown in Fig. 3. To release the lock it is only necessary to insert the key in the barrel, whereby the latch 22 is withdrawn from the bracket slot, when the key is turned.

As best illustrated in Fig. 10 and Figs. 16 to 20 inclusive, the side walls 23 of the drawer A are formed with offset longitudinal channels 23' for the reception of a double flanged wing-strip 24, which is brazed or otherwise secured to the base wall of each channel 23'.

As best shown in Figs. 10 and 19, the rear wall 23" of the drawer is provided with corner openings 25, through which are inserted a pair of toothed rack-bars 26, which rack-bars are formed with open edge beads 26' that engage the edges of the double flanged wing-strip 24. When each rack-bar is completely inserted throughout the length of the drawer, it is locked by depressing a flange 27 at the opening 25 in the rear drawer wall, to form a tooth 28, which tooth engages an outwardly extended burr 29 of the rack-bar, whereby said rack-bar is secured in its proper position.

Each rack-bar 26 is provided for adjustably locking a compression drawer panel 30. The drawer panel carries a pair of feet 31 extending in alignment with the rack-bars and said feet have crowned edges 31', which edges are in slideable engagement with the beaded edges 26' of the rack-bar. Hence, the panel is guided back and forth within the drawer by said feet.

The compression panel 30 is adjusted lengthwise of the drawer and locked in its adjusted position by a pair of reciprocative spring controlled plungers 32, which plungers are connected to the panels by means of guide slots 32' having extended therethrough pairs of shank buttons 33.

The plungers are further guided, at their inner ends, by offset straps 34 of a plate 34' secured to the panel. The ends of the plungers are folded over to form angular surfaces 35, which surfaces are engaged by the inverted V shaped ends 36 forming part of a reciprocative plate 37. The plate 37 is confined and guided in runways

$31'$, which runways form part of the bed plate $34'$.

The plungers have interposed between their angular ends a coil spring 38 , which coil spring is also confined in an offset of the bed plate $34'$. It will be noted that the upper end of the inverted V shaped plate projects above the panel and is folded over and extended downwardly for guiding and reinforcement.

From the foregoing description, in the operation, whereby the panel is moved back and forth in the drawer, the operator depresses the projecting end of the inverted V shaped plate 31 , whereby the V edges of the plate extensions 36 will engage the angular surfaces 35 of the plungers and thus contract the same in opposition to their spring pressure, whereby the plungers are withdrawn from interlocked engagement with the rack-bars 26 , and thereafter the panel is moved forward to compress the records between said panel and the front wall of the drawer. Obviously, to loosen or release the records, the panel will be moved backwardly.

I claim:

1. In a filing cabinet embodying side and front walls provided with drawer openings for the reception of slideable drawers and a universal locking means for all drawers; comprising a U shaped vertically positioned housing secured to a front corner of the cabinet adjacent to the drawer openings having slots therein opposite one side wall of each drawer, a locking bar slideably mounted in the housing, wings extending from the locking bar through the housing slots, wedge shaped fins extending from the housing adjacent the wings, individual latch bolts mounted upon the front wall of each drawer engageable with the wings and fins, a lock and release means for raising and lowering the locking bar, the same including a spring controlled stem having a key-actuated barrel connected thereto and extending through the front face of the cabinet, a bracket for supporting the barrel and stem secured to a side wall of said cabinet, a spring controlled lever

pivoted to the bracket having a slot therein, a stud extending from the stem engaging the lever slot, and a pivot connection between said lever and locking bar end.

2. In a filing cabinet embodying side walls and a front wall provided with drawer openings for the reception of slideable drawers and a universal locking means for the drawers; the same comprising a U shaped vertically positioned housing secured to the front corner of the cabinet adjacent the drawer openings having slots therein opposite one side wall of each drawer, a locking-bar slidably mounted in the housing, wings extending from the locking-bar through the housing slots, wedge shaped fins extending from the housing below the wings, individual spring controlled latch bolts mounted upon the front of each drawer engageable with the wings and fins and in the path of travel of said wings, a lever pivotally mounted at its inner end on the cabinet in rear of the locking-bar having an obliquely disposed slot therein, said lever being pivotally connected adjacent to its forward end to the locking-bar for raising and lowering the locking-bar upon swinging movement of the lever, and a key actuated spring controlled stem slidably supported by the front of the cabinet movable over the lever having a pin engaging the lever slot for swinging said lever on its pivot, whereby the locking-bar is raised or lowered to lock or release all drawers.

JOHN F. REIMER.
